UNITED STATES PATENT OFFICE.

OWEN DAVID LUCAS, OF BAYSWATER, LONDON, ENGLAND, ASSIGNOR TO VICKERS LIMITED, OF WESTMINSTER, LONDON, ENGLAND, A BRITISH COMPANY.

IGNITION SYSTEM FOR FLARES, BOMBS, AND THE LIKE ADAPTED TO BE DROPPED FROM AIRCRAFT.

Application filed October 30, 1923. Serial No. 671,676.

To all whom it may concern:

Be it known that I, OWEN DAVID LUCAS, a subject of the King of Great Britain, residing at 49 Linden Gardens, Bayswater, in the county of London, England, have invented certain new and useful Improvements in Ignition Systems for Flares, Bombs, and the like Adapted to be Dropped from Aircraft, of which the following is a specification.

10 This invention relates to an electrical system for the ignition of flares, bombs and other explosive or ignitable bodies adapted to be dropped from aircraft and has for its chief object to ensure efficient ignition electrically after the body has been dropped and to prevent risk of premature ignition, that is, ignition before the body has cleared the rack or release mechanism of the aircraft. The body to be dropped will, for convenience, usually be referred to hereinafter as a bomb, but it is to be understood that this term is meant to cover any type of fuzed body which is to be ignited after dropping.

According to this invention the fuze is provided with timing or delay mechanism adapted to be ignited electrically by an electrical ignition device controlled by current supplied through a circuit associated with release mechanism on the aircraft, at the time of release. In the construction of fuze preferred a head adapted to be engaged by a spring controlled gripping electrical switch device is provided with a pair of insulated contacts connected to the ignition device, such as a bridge wire in the fuze primer. The head is preferably mounted to swivel in the end of the fuze.

The electrical release mechanism on the aircraft supplying the fuze current as the bomb is released comprises an operating switch associated with the usual operating lever and having a safety catch which prevents the switch closing the firing circuit unless the catch is actuated, so that on moving over the operating lever without releasing the catch the bomb is dropped without ignition. The electrical release switch which grips the fuze head comprises two gripping jaws having contact pieces for the head and telescopic members attached to the bomb carrier, provided with contacts which are brought together only after the bomb has begun to drop upon its mechanical re-

lease, contact being maintained for an appreciable time by the yielding of the telescopic device which allows the gripping jaws to retain their hold until the bomb has dropped through a short distance, when the jaws are opened for complete release.

For a rack carrying more than one bomb a distributor switch is provided comprising an insulated contact arm travelling with the release bar of the rack and adapted to close the circuit connected to the release switch as the release bar passes over the release point in its travel, so that contact is made just before the release of the bomb.

In order that the said invention may be clearly understood and readily carried into effect the same will now be described more fully with reference to the accompanying drawings, in which:

Figure 1 is a sectional view, and

Figure 2 an elevation of an electrically operated fuze embodying this invention and suitable for use with flares.

Figure 3 is a sectional view of an adaptor for use with bombs, shown with the fuze in dotted lines.

Figure 4 is a plan of a safety collar employed in the bomb fuze.

Figure 5 is an elevation of the bomb fuze as fitted to an exploder tube of ordinary type.

Figures 6, 7 and 8 are respectively a side elevation, a longitudinal section and an elevation in extended position of the release switch.

Figures 9 and 10 are respectively a plan and a side view of a bomb rack adapted for electrical fuze ignition.

Figure 11 is a diagrammatic view of the ignition system associated with the rack.

Figures 12 and 13 are detail views of a distributor switch on the rack; and

Figures 14 and 15 are respectively a section and an elevation of an operating switch lever.

Referring first to the construction of fuze illustrated in Figures 1 and 2 and adapted for use with flares, the fuze body comprises the main fixed ring A (shown with a time scale *a* marked upon its flange), the base B which is screwed into the body of the flare, the upper fixed ring C with channel *c* for the fuze composition and the cap D screwed on

to the upper screw threaded part a^1 of the ring A. The boss b of the base B is screwed into the ring A and carries the fuze primer E in which is the electrical ignition device, such as a current heated bridge wire connected to the lead e . F is the contact head comprising the two contact members f , f^1 separated by the insulating piece f^2 , the contact f^1 being made in one with the stem 10 f^3 which passes through the cap D and is secured in the cap by the ring f^4 into which it is screwed, the head F being free to rotate around its axis in the cap D without interfering with the contact mechanism. 15 The contact f is electrically connected by the pin f^5 to the insulated centre pin f^6 receiving the end of the spring pressed contact rod f^7 , the lower end of which is pressed by the spring against the pin e^1 20 connected to the ignition lead e . The ignition circuit is therefore through the contact f , rod f^7 , lead e to the fuze primer and back through the fuze body to the contact f^1 . The head F is adapted to be gripped between 25 contact making gripping jaws as herein-after described. When ignition is effected at the primer E the composition in the ring C is fired through the flash channel a^2 and this in turn ignites the composition in the 30 adjustable ring G situated between the fixed ring C and the flange of the ring A. The adjustment of the ring G determines in the usual manner the delay period between the ignition of the fuze and the firing of the 35 charge.

Figures 3, 4 and 5 show the application of the method to a bomb fuze to be fired on impact, the electrically operated fuze serving to arm the bomb by removing a safety 40 ring H at the base of the fuze after a pre-determined interval from the release of the bomb. The body of the fuze is on the lines already described, the timing ring being used to determine the moment when the 45 bomb is armed after leaving its carrier as the object is to arm the bomb after it has safely cleared the aircraft. B¹ is the fixed supporting member which is screwed into the head of the usual exploder tube J¹ of 50 the bomb and the striker J projects from the end of a member j connected to the supporting member B¹ by the shearing pin j¹. The safety ring or disc H is made in two parts, as shown in Figure 4, which can 55 be separated so as to fall away from the fuze for arming purposes. When the safety ring is in place as shewn in the drawings, the base B² of the electrical fuze is separated from the fixed member B¹ carried by the 60 bomb, so that the fuze body and striker J cannot move forward relatively to the bomb. If, however, the safety ring H is removed, on the bomb striking the complete fuze body will move forward by its inertia, shearing the pin j¹ and allowing the striker J to op-

erate. The safety pin h^x is removed after the bomb is loaded into the carrier in the usual way.

Figure 5 shows the fuze of Figure 3 assembled on the exploder tube J¹ of the bomb, the part B¹ being screwed into the exploder head so that the striker J is over the cap of the exploder detonator in the usual way.

The safety ring H is removed during the dropping of the bomb by the firing of the electrical fuze. The two sections of the ring H are secured in place on the bottom of the fuze body by the lugs h extending into corresponding recesses at opposite sides of the base B², and the shearing pins h¹ which project through the lugs h and the base B² near the edge, as shown especially in Figure 4. Inside the base B² immediately behind the lugs h are small pistons or plugs b¹ within which are explosive charges b² fired through the flash passages b³ by the fuze at the end of the period determined by the length of fuze composition. On ignition of the small explosive charges b² during the fall of the bomb the plugs b¹ drive out the ring lugs h breaking the shearing pin h¹ and causing the two ring sections to be blown away from the base of the fuze. When the ring H is thus removed the bomb is armed, as on impact the complete fuze with striker is free to move forward and explode the bomb, which is, of course provided with the usual impact firing means.

Referring to Figures 6, 7 and 8 showing the contact clip and switch connected for ignition purposes to the head F of the fuze, K is the switch body of fibre or other suitable insulating material, provided at one side with the suspension plate k having a 100 number of perforations k¹, any one of which may serve, by means of a detachable pivot pin, for suspension of the clip from the bomb rack or support hereinafter described. The arrangement allowing the clip 105 to be connected to the fuze head at any angle desired. The contact clip comprises the two jaws L each having a small cupped contact piece l adapted to grip on the contacts f, f¹ of the fuze head, the jaws being controlled by the spring l¹ passing through the jaw carrying plug M screwed into the sliding sleeve m through which passes the rod m¹ within the spring m² and terminating in the mushroom contact head m³. The leads 110 N, N¹ passing from the source of current on the bomb rack or support are connected respectively to the mushroom head m³ and to the contact l at one side of the clip, a short lead N² passing from the other contact l 115 along the opposite side of the clip body to the contact ring n on the upper end of the body.

The sleeve m and rod m¹ are telescopic and the sleeve is also free to slide within 120

the clip body, the action of the device being as follows:—When the bomb is released the head F engaged by the contact jaws L pulls down the jaws along with the sleeve m until 5 the mushroom head m^3 meets the contact ring n when the electrical circuit is closed and the fuze ignited. Ignition, however, cannot take place before the release of the bomb as the circuit is not closed until the 10 bomb has actually dropped a short distance. To ensure that the circuit shall be closed through the fuze for a sufficient time to provide for certain ignition, after contact has been made by the mushroom head m^3 the 15 contact jaws L do not release the fuze head until the latter has dropped through a substantially greater distance. To permit of this the leads N, N^2 which are attached both to the clip body and to the upper ends of 20 the gripping jaws L are provided with a certain length n^1 of normally slack cable, so that when the rod m^1 has reached the end of its travel on the head m^3 abutting on the ring n the sleeve m, with the plug M 25 and the gripping jaws, is free to slide to a further distance against the pressure of the spring m^2 and the sleeve and attached parts extend downwardly into the position shown in Figure 8, when the lengths n^1 become 30 taut and pull open the jaws L, if in the meantime the increased tension of the spring m^2 has not already caused the jaws to open against the spring l^1 .

Referring to the bomb rack and electrical ignition mechanism illustrated in Figures 35 9 to 13, the construction of the rack apart from the electrical control forms no part of the present invention. The rack comprises the frame O mounted in a known 40 manner in the aircraft and provided with the base o on which the rack mechanism is mounted. This comprises a sliding release bar P provided with ratchet teeth p each corresponding to a step in the movement of 45 the bar and an operating lever Q carrying a pawl q adapted to engage at each forward movement of the lever with a tooth p and to displace the bar forward to the left of Figure 9 against the spring p^1 , a detent pawl 50 p^2 preventing return of the bar. The lever Q is operated from the switch lever herein-after described through the Bowden wire or other connection q^1 .

R, R are hooks serving to support the 55 bombs or flares (X, X in Figure 11), which are provided with suitable attachments engaging the hooks. The hooks are held in supporting position by the pivoted catches r, the first, third and fourth of which are 60 shown in engaging position, while the second has already been released to allow the bomb to drop. The catches r are released in succession, one at each forward movement of the bar P, by shoulders p^3 formed 65 by means of recesses at the side of the bar,

a shoulder, as the bar is displaced towards the left, meeting the corresponding pivoted catch r and pushing it over past the lever arm p^1 of the hook R. The shoulders p^3 are positioned on the bar so that the catches 70 are released successively as the bar is slidden from right to left through successive steps, one for each operation of the lever Q.

Brackets o^1 , one for each bomb, project 75 at the side of the rack and serve to carry the contact clip device shown in Figures 6, 7 and 8 by means of the pins o^2 at their ends. the pin of any bracket being passed through any one of the holes k^1 in the perforated plate or web k of the clip body K. The 80 bomb is, therefore, supported both by the hook R and at the fuze end by the corresponding bracket o^1 which, however, does not take any substantial part of the weight 85 of the bomb until the latter is released from its hook.

The rack illustrated is to carry four bombs or flares X to be released in succession and, in order that each fuze shall be ignited upon dropping, electrical circuits are arranged as indicated in the diagram Figure 11, a battery S being provided on the aircraft connected at one pole to the succession of leads N belonging to the release 90 switches and at the other pole through the 95 switch T to the distributor U which carries a series of four contacts u, one for each fuze, the four contacts being connected, respectively, to the leads N^1 of the corresponding 100 contact clips. The distributor is shown in detail in Figures 12 and 13 and the circuit through successive fuze clips is closed by the contact member p^4 on the release bar P. As will be seen from the diagram Figure 11 105 when the contact member p^4 meets the first contact u of the distributor U the circuit is made for the second fuze counting from the left of Figure 9, while the circuits for the successive fuzes are closed at the distributor 110 as the contact member p^4 moves with the release bar P from right to left, the final contact being made for the left-hand fuze as the final catch r is released by the end of the release bar P.

The operating switch lever T is shown 115 separately in Figures 14 and 15 and carries the switch arm V with spring v and switch member v^1 which normally abuts against a shoulder t at the upper part of a recess t^1 in the lever T. A thumb switch v^2 is connected to the member v^1 and if pressed down as the operator pulls the lever T the switch arm moves the member v^1 clear of the shoulder t and causes it to enter the recess t^1 and project between the contacts t^2 , t^3 the 125 lower one of which is pressed up by the spring t^4 . The contacts t^2 , t^3 are connected by the leads s, s^1 respectively to one pole of the battery S and to the distributor U, so that the battery circuit is completed 130

through the distributor, and therefore through the fuze of the bomb being released, when the release switch K operates as hereinbefore described.

The connection η^1 from the operating lever Q is attached to the arm t^5 of the lever T and on pulling over the lever T the lever Q is moved over and displaces the release bar P through one step. If the catch v^2 is not pressed down the bomb X is released without ignition of the fuze, but if the catch c^2 has been operated the switch arm V closes the ignition circuit and ignition of the fuze takes place on release of the bomb.

While a rack for dropping a succession of bombs has been shown, the ignition system is equally applicable to a single bomb release device or to release mechanism for any desired number of bombs. The operating lever T moreover is not necessarily provided with the electrical switch device, as this may if required be separate from the lever and separately actuated.

What I claim and desire to secure by Letters Patent of the United States, is:—

1. In a fuze for fuzed bodies adapted to be dropped from aircraft which have a gripping contact device, a projecting member on the fuze adapted to be held by said gripping contact device, a timing device provided with fuze composition, an electrical ignition device adapted to ignite the said composition, said projecting member having a pair of electrical contacts insulated from each other and connected to the electrical ignition device.

2. In a fuze for fuzed bodies adapted to be dropped from aircraft, a timing device provided with fuze composition, an electrical ignition device adapted to ignite the said composition, a projecting head mounted to swivel in the end of the fuze, a pair of external contacts on the head, which contacts are insulated from each other, and an electrical connection from one of the said head contacts to the electrical ignition device, the said connection including a rubbing contact surface allowing the swivelling head to turn while maintaining the electrical connection.

3. In a fuze for fuzed bodies adapted to be dropped from aircraft, time rings provided with fuze composition, an electrical fuze primer adapted when energized to ignite the said composition, a fixed central contact in the fuze body connected to the said primer, a fuze cap, an external projecting head mounted to swivel in the said fuze cap, the said head having a pair of external contacts insulated from each other, and a spring pressed contact member in the said head connected to one of the insulated head contacts and adapted to press on the said fixed contact, for the purpose specified.

4. In a fuze as claimed in claim 1 adapted

for use with bombs, a striker mounted on the fuze and adapted for impact firing of the bomb, a fixed support for the fuze, a safety distance piece interposed between the fuze body and the fixed support and fuze 70 fired explosive means ignited by the fuze composition at the end of a predetermined delay period, which explosive means on operation blows out the said distance piece and arms the impact fuze.

5. In a fuze as claimed in claim 1 adapted for use with bombs, a striker mounted on the fuze and adapted for impact firing of the bomb, a fixed support for the fuze, a distance piece in the form of two transversely 80 divided collar members interposed between the fuze body and its fixed support, means for holding the two collar members in position, and a small outwardly driving explosive charge provided for each collar member and adapted to be ignited by the fuze composition at the end of a predetermined delay period, the said explosive charges driving outwardly the collar members and arming the impact fuze.

6. In release and electrical ignition mechanism for fuzed bodies having a fuze and provided with a contact carrying head, means for holding and releasing the fuzed body, an extensible release switch adapted 95 to hold the aforesaid fuze contact head, means for closing the electrical circuit after a predetermined movement of the said switch on release of the fuzed body, and means for releasing the fuze head after a further movement of the switch, the ignition circuit being maintained closed until the release of the head, for the purpose specified.

7. A release switch as claimed in claim 6, 105 provided with a projecting web having a number of perforations adapted for use in suspending the said switch from the aircraft in any one of a series of positions.

8. In release and electrical ignition mechanism for fuzed bodies having a fuze provided with a contact carrying head, an extensible release switch comprising spring controlled contact making and gripping 110 jaws adapted to hold the aforesaid fuze contact head, a telescopic spring controlled member carrying the said gripping jaws, a fixed contact, a co-operating movable contact on the telescopic member, adapted to meet the fixed contact after an initial movement of the said member, and means for opening the gripping jaws automatically 115 after a predetermined extension of the telescopic member, for the purpose specified.

9. In release and electrical ignition mechanism for fuzed bodies having a fuze, provided with a contact carrying head, an operating lever effecting the release of the said fuzed body, an electrical fuze release switch adapted to engage the contacts on the said 120

75

fuze and an operating switch associated with the operating lever and adapted to close part of an electrical ignition circuit which passes through the said fuze release switch.

- 8 10. In release and electrical ignition mechanism for fuzed bodies having a fuze provided with a contact carrying head, an operating lever effecting the release of the said fuzed body, an electrical fuze release
- 10 switch adapted to engage contacts on the said fuze, an electrical switch arm mounted on the said operating lever and provided with a catch which prevents closing of the switch until the catch is moved into free position and an electrical ignition circuit controlled by the said switch arm and passing through the said fuze release switch.

- 11. In a release and electrical ignition system for fuzed bodies adapted to be dropped from aircraft, means on the aircraft for supporting a fuzed body, means for releasing the said body at will, an independent attachment on the aircraft for the fuze of the said body, an electrical ignition circuit adapted to be completed through the said fuze connection, and means for completing the circuit only after a predetermined movement of the fuzed body subsequent to its release.

- 20 12. In a release and electrical ignition system for fuzed bodies adapted to be dropped from aircraft, an aircraft rack provided with means for supporting the said fuzed bodies and for releasing them in succession and with separate detachable connecting means for the fuzes of the said bodies, an electrical ignition circuit on the aircraft adapted to be completed through the said fuze connecting means, and means
- 25 30 for completing the circuit through a fuze connection only after a predetermined movement of a fuzed body subsequent to its release.

- 35 40 45 13. In a release and electrical ignition system for fuzed bodies adapted to be dropped from aircraft, an aircraft rack

adapted to release in succession a number of fuzed dropping bodies, a fuze release switch for each fuze with which it is adapted to engage, a series of electrical firing circuits connected up through the said release switches and a distributor switch on the rack adapted to close the said electrical firing circuits in succession at successive operations of the rack, for the purpose specified. 50 55

14. In a release and electrical ignition system for fuzed bodies adapted to be dropped from aircraft, an aircraft rack adapted to release in succession a number of fuzed dropping bodies, a fuze release switch 60 for each fuze with which it is adapted to engage, a series of electrical firing circuits connected up through the said release switches, a distributor switch provided with a series of contacts each in one of the aforesaid firing circuits, a sliding member on the rack moved step by step at the release of successive fuzed bodies and a contact maker on the said sliding member adapted to make contact successively with the contacts of the 65 distributor switch immediately before the corresponding fuzed bodies are released.

15. In a release and electrical ignition system for fuzed bodies adapted to be dropped from aircraft, an aircraft rack 75 comprising a supporting frame, means for detachably securing a series of fuzed dropping bodies, a sliding release bar adapted to release the said bodies from their securing means in succession, means for moving the 80 release bar step by step, a series of supporting brackets corresponding in number to the dropping bodies, a source of electrical current on the aircraft, a series of electrical release switches suspended from the aforesaid 85 supporting brackets and adapted for electrical connection to the fuzes of the dropping bodies, and means operated by the aforesaid sliding release bar for completing a circuit through the release switches in suc- 90 cession.

OWEN DAVID LUCAS.
